CLAIM

The ornamental design for a work light, as shown and described.

DESCRIPTION

FIG. 1 is a first perspective view of a work light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the work light thereof; and,

FIG. 10 is a perspective view of another state of the work light thereof.

The broken lines shown in the drawings depict portions of the work light that form no part of the claimed design.

1 Claim, 10 Drawing Sheets
